UNITED STATES PATENT OFFICE.

WILLIAM D. MURRAY, OF PLAINFIELD, NEW JERSEY, AND FREDERICK B. SCHENCK, OF BROOKLYN, NEW YORK, ASSIGNEES TO THE INTERNATIONAL COMMITTEE OF YOUNG MEN'S CHRISTIAN ASSOCIATIONS, OF NEW YORK, N. Y.

DESIGN FOR A BADGE.

SPECIFICATION forming part of Design No. 26,625, dated February 16, 1897.

Application filed May 28, 1896. Serial No. 593,516. Term of patent 14 years.

To all whom it may concern:

Be it known that we, WILLIAM D. MURRAY, of Plainfield, in the county of Union and State of New Jersey, and FREDERICK B. SCHENCK, of Brooklyn, in the county of Kings and State of New York, citizens of the United States, have invented and produced a new and original Design for a Badge, of which the following is a specification.

10 In the drawing we have represented our design by an elevation.

The leading feature of our design for a badge consists in the shape and ornamentation, as shown in the drawing.

The triangle c, with the representation of an open book d, is surrounded by a ring a, which intersects the points of the triangle, and the monogram b, composed of the letters "X P," appears behind the book and triangle.

What we claim is—

20 The design for a badge substantially as shown and described.

Signed by us this 22d day of May, A. D. 1896.

WM. D. MURRAY.

FREDK. B. SCHENCK.
